(57) **CLAIM**

The ornamental design for a utensil handle, as shown and described.

DESCRIPTION

FIG. 1 is a perspective view of an embodiment of the utensil handle;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is another perspective view thereof; and,

FIG. 9 is another perspective view thereof.

In the Figures, utensil elements are shown in broken lines for illustrative purposes only and form no part of the claimed design.
